UNITED STATES PATENT OFFICE.

CHARLES D. PARNHAM, OF ATLANTA, GEORGIA.

LUBRICATING DEVICE.

945,474.

Specification of Letters Patent.

Patented Jan. 4, 1910.

Application filed July 13, 1909. Serial No. 507,449.

To all whom it may concern:

Be it known that I, CHARLES D. PARNHAM, a citizen of the United States, residing at Atlanta, in the county of Fulton and State 5 of Georgia, have invented certain new and useful Improvements in Lubricating Devices, of which the following is a specification.

This invention relates, in general, to 10 means for greasing the bearings of machinery, and its object is to provide a light and simple device that may be operated by hand to force thick grease or dope into the oil-holes in machinery.

15 To this end my invention consists in the construction and combination of parts forming a lubricating device hereinafter more fully described, and particularly set forth in the claims, reference being had to the 20 accompanying drawings in which—

Figure I shows in side elevation a lubricating device according to my invention, the piston being out for the cup to receive a charge of grease, and a part of the lever 25 broken away. Fig. II shows a vertical section of the same on the irregular line α Fig. III, partly in side elevation. Fig. III shows a horizontal section at line γ Fig. II.

Numeral 5 represents the body of the 30 device, consisting of a cylindrical cup, of thin metal, open at the top and having at its lower end, a tapering nozzle 6, connected with the cylinder by a truncated cone 7, having neatly curved sides. The top 35 edge 8, may be stiffened by turning it into a flange or by wiring it if necessary. A handle 28, is provided with a ring 9, which fits freely around the body 5, under the flange 8, and has passages 10, down its inner side, through which lugs 11, fixed on 40 the cylinder, may pass to enter the cup downward into the ring. When thus entered, the cup may be rotated a little in the ring to bring the lugs under a solid portion 45 thereof, to keep the cup from being unintentionally removed in service.

An arm 12, projects radially from the ring at the side opposite to the handle 28, and serves as the bearing or fulcrum of a lever 50 13, which is pivoted thereto by a pin 14. A rod 15, pivoted at 16 to the lever, connects with the piston 17, by means of a pin 18. A packing 19, fitting the interior of the cylinder, is held upon the piston by a collar 55 20, and bolts 21.

The piston is formed with a deep recess

22, to receive the connecting rod 15, in order that this rod may be attached at a point considerably below the plane of bearing of the piston at the packing ring 19. Thus, 60 while the rod 15, operates with a pushing movement in service, its action on the piston is to pull it downward against circumferential resistance, or the resistance of any substance in the cup. This tends to keep the 65 piston in its proper plane at right angles to the line of the cylinder. A valve 26, permits air to pass through the piston to relieve it from air pressure when being withdrawn.

In operation the lever 13, is to be raised 70 and thrown over back until it rests on the shoulder 23, on arm 12; taking the piston out of the cup and away from its mouth, as shown in Fig. I. Now the cup is to be charged with the amount of grease required. 75 A shoulder 24, on the lever, supports the rod 15, with the piston in position to re-enter the cup when the lever is brought forward. Now if the nozzle 6, be inserted in the oil hole of a machine bearing and the 80 lever 13, be pressed downward the required amount of grease may be forced into the bearing. The curved sides 7, may be made by the usual process of stamping or spinning sheet metal, with the idea of making the 85 whole body integral and ornate in appearance; but the body can be more cheaply made with the sides of the cone straight, as shown in dotted lines 25. If desirable the device may be further cheapened by using 90 rivets in place of the bolts 21, but the screw bolts are more readily removable for adjusting or replacing the packing 19, when it becomes worn in service. By means of this lever pressed piston, grease or dope of any 95 practicable degree of thickness may be readily forced into the oil holes in machinery. The device may be very cheaply constructed or it may be made to any degree ornate. 100

Having thus fully described my invention, what I believe to be new and desire to secure by Letters Patent is particularly stated in the following claims.

1. In a lubricating device, a cylindrical 105 cup wide open and flanged at one end and conical with a nozzle delivery at the other end; lugs fixed upon the cylindrical portion below the flange; a handle having a ring to receive the cup and to support it by the 110 flange, the ring having passages down its inner face to admit the said lugs; an arm

projecting radially from the ring at the side opposite to the handle; a lever pivoted upon this arm; a rod pivoted at one end to the lever and at the other end to a piston; a packing ring fitting the piston to the cup; a collar over the packing; the piston having a recess in its upper side, and the said rod pivoted to the piston in that recess at a point below the circumferential bearing plane of the piston.

2. In a lubricating device, a cylindrical

cup; a piston fitted for circumferential bearing in the cup and having a recess in its outer side; and a rod pivoted to the piston within said recess at a point below the said circumferential bearing.

In testimony whereof I affix my signature in presence of two witnesses.

CHARLES D. PARNHAM.
